United States Patent Office

Des. 217,039
Patented Mar. 24, 1970

217,039

MAILBOX

Gregory O. Corkery, St. Louis, Mo., assignors to Jackes-Evans Manufacturing Company, St. Louis, Mo., a corporation of Delaware

Original design application July 17, 1968, Ser. No. 12,801, now Patent No. 215,510, dated Sept. 30, 1969. Divided and this application Feb. 10, 1969, Ser. No. 15,893

Term of patent 14 years

Int. Cl. D31

U.S. Cl. D74—9

Fig. 1.

Fig. 2.

Fig. 3.

FIGURE 4FIGURE 5

FIGURE 1 is a front elevational view of my new design for a mailbox illustrating the contrasting wood applique on the hinged lid;

FIGURE 2 is a top plan view of the mailbox shown in FIGURE 1;

FIGURE 3 is a side elevational view, the opposite side presenting a mirror image;

FIGURE 4 is a rear elevational view; and

FIGURE 5 is a bottom plan view.

This a division of my application Serial No. D. 12,801, filed July 17, 1968 and now patent No. D. 215,510 granted on September 30, 1969.

I claim:

The ornamental design for a mailbox, substantially as shown and described.
